2,421,843

ACCUMULATOR FUEL INJECTION SYSTEM

Donald E. Meitzler, Manchester, Conn., assignor
to United Aircraft Corporation, East Hartford,
Conn., a corporation of Delaware

Application July 23, 1943, Serial No. 495,928

6 Claims. (CL 103—41)

1

This invention relates to accumulator injection apparatus.

For airless injection of fuel the accumulator chamber of apparatus of this type must be free from air bubbles. In a stationary installation, venting of the top point in the accumulator chamber during a part of the stroke of the injection plunger is sufficient for removing air from the chamber. Where the engine is mounted in a vehicle, particularly an aircraft, the injection apparatus may be tipped so that the vent port in the accumulator chamber is no longer at the top. A feature of this invention is the venting of the accumulator chamber regardless of the position of the chamber.

Another feature of this invention is an accumulator injection apparatus which may be installed in any position without affecting the proper venting of the accumulator chamber.

Another feature is an arrangement of several spaced ports in the accumulator chamber so that at least one of the ports will be substantially at the top of the chamber regardless of the position of the chamber.

Other objects and advantages will be apparent from the specification and claims, and from the accompanying drawing which illustrates an embodiment of the invention.

Fig. 1 is a sectional view through the injection apparatus.

Fig. 2 is a fragmentary sectional view showing the plunger at the other end of its stroke.

The casing 10 has a bore 12 in which is a plunger 14. With the plunger in the position shown in Fig. 2 before it begins its injection stroke, an inlet port 16 admits fuel to the end of the bore 12. During the injection stroke fuel is forced by the plunger 14 into accumulator chambers 18 and 20 through a groove 22 in a valve 24 and cross-passage 26. This valve is slideable in a bore 28 in a ring 30 in the casing.

While fuel is being forced into the accumulator chambers, valve 24 closes a passage 32 which connects passage 26 with the discharge nozzle 34. One end of valve 24 is in line with a seat 36 at the end of passage 32 and is held on this seat by pressure of fuel on the other end of the valve during the injection stroke of the plunger. Groove 22 extends longitudinally of valve 24 to permit a throttled flow of fuel past the valve into the accumulator chamber. The end of valve 24 remote from seat 36 is conical to engage a seat 38 at the end of bore 28 communicating with bore 12, and to close the end of groove 22.

Discharge of fuel through passage 32 may be

2

controlled by a check valve 40 held against a seat by a spring 44. When accumulator valve 24 moves to open passage 32, fuel pressure opens the check valve 40 and fuel discharges past the check valve until the pressure of spring 44 is greater than the pressure differential holding the valve open. The check valve may have an integral plunger 46 slideable in a bore 48 in nozzle 34, the plunger having a longitudinal groove 50 for flow of fuel past the plunger. Nozzle 34 has one or more openings 52 for discharge of fuel.

Air in the accumulator chambers 18 and 20 is vented through a passage 54 in casing 10 which connects with the chambers. The opposite end 18 of passage 54 forms a port 56 in bore 12 opposite a relief port 58 which may be connected to a drain. Plunger 14 has a groove 60 which during the plunger stroke connects ports 56 and 58 so that any air in the accumulator chambers is discharged through the passage (see Fig. 2).

Each accumulator chamber is substantially cylindrical and the opposite ends of each chamber are provided with a series of ports 62 and 64 which connect with passage 54. The ports of each series are uniformly spaced about the periphery of the cylinder wall so that one of the ports will be at the high point of the chamber in substantially any position of the cylinder. A ring 66 having a conical inner surface may be positioned in the inner end of each cylindrical chamber, and the ports 64 are formed as grooves in the outer surface of this ring. All of these ports connect with an annular groove 70 in the periphery of the ring with which passage 54 communicates. Ports 62 may be formed in a plug 72 defining the outer end of the chamber, and these ports all communicate with an annular groove 74 connecting with passage 54.

By the arrangement of the series of ports 62 and 64 as shown, the injection apparatus may be placed in any position without affecting the proper venting of the chambers, since, as above stated, one of the ports will be at substantially the high point of the chamber in almost any position of the apparatus.

During the pumping stroke of the plunger, the head of the plunger closes inlet port 16 and port 56 is closed by the edge of groove 60. As the plunger continues its pumping stroke with these ports closed, fuel is accumulated under pressure in the chambers until port 16 is uncovered by groove 60. When this occurs, fuel from the space at the head of the plunger discharges through a passage 76 extending from the head of the plunger to groove 60. The resulting reduction in pres-

sure in the plunger bore causes valve 24 to move endwise, opening passage 32 for the discharge of fuel from the accumulator chambers through the nozzle. As the conical valve surface now engages valve seat 38, flow of fuel through groove 22 is prevented. Accumulator valve 24 is again moved to engage seat 38 when the plunger begins its next pumping stroke.

During the return stroke of pump plunger 14, groove 80 connects ports 58 to 58 and the pressure remaining in chambers 18 and 20 forces out through passage 54 any air that may be in these chambers. Thus during each stroke of the pump plunger, the accumulator chambers are vented to prevent the accumulation of gas or air bubbles.

It is to be understood that the invention is not limited to the specific embodiment herein illustrated and described, but may be used in other ways without departure from its spirit as defined by the following claims.

I claim:

1. Injection apparatus comprising a pump, an accumulator chamber in which fuel is accumulated by said pump, and means for venting said chamber in any position of the chamber to remove gas bubbles collecting therein, said means including several ports in the chamber so arranged that at least one of the ports will be at the high point of the chamber in substantially any position of the chamber.

2. Injection apparatus comprising a pump, a substantially cylindrical accumulator chamber in which fuel is accumulated by said pump, and means for venting said chamber in any position of the chamber to remove gas bubbles collecting therein, said means including several spaced ports located around the peripheries of the end walls at each end of the chamber so arranged that a port will be substantially at the high point of the chamber in any position of the chamber.

3. Injection apparatus comprising a pump, an accumulator chamber in which fuel is accumulated by said pump, and means for venting said chamber in any position of the chamber to remove gas bubbles collecting therein, said means including several spaced ports at each end of the chamber so arranged that a port will be substantially at the high point of the chamber in any position of the chamber, and a connection between said ports and a vent.

4. Injection apparatus including a pump, a

substantially cylindrical accumulator chamber in which fuel is accumulated by said pump, and means for venting said chamber in any position of the chamber to remove gas bubbles collecting therein, said means including several spaced ports at each end of the chamber, so arranged that a port will be substantially at the high point of the chamber in any position of the chamber, and a connection between said ports and a vent.

10 5. Injection apparatus comprising a movable pump plunger, a casing having a bore for said plunger, an accumulator chamber in which fuel is compressed by said plunger, means for venting said chamber for removing gas collecting therein including several spaced ports in the chamber so arranged that a port will be substantially at the high point of the chamber in any position of the chamber, a connection from said ports to a port in the plunger bore, and means on the plunger 15 for connecting the port in the bore to a vent during a part only of the plunger stroke.

15 6. Injection apparatus comprising a movable pump plunger, a casing having a bore for said plunger, an accumulator chamber in which fuel is compressed by said plunger, means for venting said chamber for removing gas collecting therein including several spaced ports in the chamber so arranged that a port will be substantially at the high point of the chamber in any position of the chamber, a groove in said plunger, opposed ports 20 in the bore adapted to be connected by the plunger, one of said ports being a vent and the other port being connected to the ports in the accumulator chamber.
